UNITED STATES PATENT OFFICE.

GEORGE W. STARR AND JOHN HENRY COGSWELL, OF HAVANA, ILLINOIS.

EXPLOSIVE GAS-ENGINE.

SPECIFICATION forming part of Letters Patent No. 585,127, dated June 22, 1897.

Application filed August 26, 1896. Serial No. 603,991. (No model.)

To all whom it may concern:

Be it known that we, GEORGE W. STARR and JOHN HENRY COGSWELL, citizens of the United States, residing at Havana, in the 5 county of Mason and State of Illinois, have invented certain new and useful Improvements in Explosive Gas-Engines; and we do declare the following to be a full, clear, and exact description of the invention, such as will 10 enable others skilled in the art to which it app pertains to make and use the same, reference being had to the accompanying drawings, and to the letters of reference marked thereon, which form a part of this specification.

15 This invention relates to certain new and useful improvements in explosive gas-engines, and especially to a mechanism by means of which the supply of gas which is automatically fed into the cylinder may be easily 20 regulated by causing a sliding stem having on one side a wedge-shaped surface which is thrown into the path of a vertically-movable piston-stem to limit its throw and the feeding of the gas through an aperture controlled by 25 a valve mounted on the said vertically-movable stem. In connection with the member having the inclined or wedge-shaped surface a series of steps on the reverse side thereof is provided, whereby a full or a half charge 30 may be fed into the cylinder or the charge shut off entirely.

A further part of our invention resides in the provision of means for regulating the exhaust-valve mechanism operated from an 35 eccentric and in which an alternating wheel is utilized to regulate the throw of the stem of the exhaust-valve, which wheel is caused to make partial revolutions by means of a swinging pawl engaging with a ratchet-wheel 40 mounted on the shaft to which the alternating wheel is keyed as the pitman connected to the eccentric and the casing carrying the alternating wheel reciprocates. Heretofore in exhaust-regulating means in connection 45 with gas-engines springs have been utilized which act under their greatest tension when the exhaust-valve is raised from its seat, whereas with our invention the tension of the spring acting on the exhaust-piston stem is 50 greatest after the valve is seated, which will be hereinafter more fully described.

To these ends and to such others as the in-

vention may pertain, the same consists, fur ther, in the novel combination and adaptation of the parts, as will be fully described in de- 55 tail and then specifically defined in the ap pended claims.

We clearly illustrate our invention in the accompanying drawings, which, with the let ters of reference marked thereon, form a part 60 of this application, and in which drawings similar letters of reference indicate like parts throughout the several views, in which—

Figure 1 is a vertical sectional view through a gas-engine embodying our invention. Fig. 65 2 is a side elevation showing the means for turning the alternating wheel. Fig. 3 is a de tail view of the valve and sliding wedge-shaped member for controlling the throw of the feeding-valve. Fig. 4 is a detail view of 70 the alternating wheel, together with the ratchet-wheel for turning the same. Fig. 5 is a detail view of regulating-stem reversed. Fig. 6 is a detail view of the two adjusting-nuts. 75

Reference now being had to the details of the drawings by letter, A designates the cylinder, in which works a plunger B, operated by a pitman connected to a crank on the driving-shaft. Slidably held on the main 80 driving-shaft C is a collar C', connected to the ends of angle-levers d, which are pivoted to a projection of the driving-wheel D, the said angle-levers carrying governor-weights, all of common construction. 85

E is the supply-valve, which is mounted on a stem E' and is designed to work vertically in a hole e, which forms a guide therefor in the casing of the valve-chamber. Leading into the chamber e' beneath the valve E is 90 the supply-pipe E², through which gas is ad mitted to the engine. The stem E' has an elongated aperture, in the bottom of which is seated a hardened-steel block F, the upper edge of which is beveled, as clearly seen in 95 the drawings. Mounted in a slot at right an gles to the stem E' and passing through the elongated aperture in said stem is the hori zontally-movable shaft G, which has its outer end threaded and carrying the adjusting-nuts 100 H, which have hubs passing through an aperture in the upper end of the lever I. The said lever I is fulcrumed at I', and its lower end, which is forked, embraces the sliding

collar C'. The upper end of the lever I has a lug *i*, on which is supported one end of a coiled spring I², the other end of the spring being supported on a lug extending out from 5 the side of the valve-chamber casing. This spring is provided to coöperate with the governor-weight (not shown) within the wheel D, which normally holds the lever I in the position shown in Fig. 1. The shaft G has a 10 portion of its surface on its lower side cut away at an angle, as seen at G', this inclined surface being in a plane parallel with the inclined surface of the hardened-steel block F and having an integral lug *g* at the outer termination of said inclined surface. On the 15 reverse side or upper edge of the said shaft G, opposite the said inclined surface G', is a series of steps *g'*, provided for a purpose which will hereinafter appear. It will thus 20 be seen that as the driving-shaft works faster or slower the governor-weights will be thrown out by centrifugal force or by gravity, aided by springs, will be drawn back, and the shaft G will be moved accordingly backward or 25 forward through the medium of the pivoted lever I, allowing a shorter or a longer play to the vertically-working valve-stem E', which will regulate the feeding of gas to the cylinder. As the engine reaches its maximum 30 speed the governor, as ordinarily used in other gas-engines, admits a very small quantity or, we might say, a "seeping" of the gas, said amount being so small as not to be considered good economy, as most of the power is 35 wasted in filling the combustion-chamber. To avoid said leakage, we provide the step or lug *g*, which holds the valve firmly to its seat, while with the slightest fall in speed the step is withdrawn and a light working charge ad- 40 mitted. As the inclined surface G' is pro- 45 vided to admit a variable amount of gas to the cylinder, when it is not so important to have a steady motion, a series of steps is ar- 50 ranged on the opposite side of the shaft G, whereby either a full or a half charge may 55 be admitted to the cylinder or the supply cut off entirely. This feeding mechanism may be easily changed from one form to the other by simply removing the shaft G and revers- 60 ing the same. In case the shaft G, having the series of steps, is reversed, so that the steps will come on the under side, the steel block F is turned so that its highest portion will come next to the steps, as will be seen 65 plainly in the detail figure of the drawings.

K is an exhaust-valve mounted on a stem K', and K² a pipe to carry off the exhaust products from the exploded gas. Working vertically in a hollow casting L, secured to the 60 side of the engine, is the casing M, in which are carried the stem K' of the exhaust-valve and means for regulating its throw, which consists of an alternating wheel N, having apertures through the same at right angles to each 65 other of such a diameter as to permit the lower end of the stem K' to pass through an aperture when the wheel is turned, so that the

said stem will register therewith. Interposed between the nut O and the jam-nuts P, which latter are mounted on a screw-threaded portion of the stem K', is a spring Q, the tension of which is regulated by raising or lowering the said jam-nuts. The casing M is caused to reciprocate up and down by connection with an eccentric R on the main driving-shaft 70 through the medium of the pitman R'. On the end of the shaft N', which is integral with the alternating wheel, is a ratchet-wheel N², with a spring n interposed between the inside of the casing M and a nut on the end of the shaft N', which spring is provided to take up 75 wear.

S is a pawl having forked arms S' and S², and each arm is pivoted to a stationary portion of the casing of the engine. One end of an arm, as S², is provided with an elongated slot s, so as to allow a slight swinging motion to the pawl as the ratchet-wheel rises, allowing the pawl to clear; but on the downward movement of the ratchet-wheel the pawl will fall by gravity, so that its hooked end will catch onto a tooth of the ratchet-wheel and cause the latter to make a partial revolution and with it the shaft and the alternating 80 wheel. The mechanism is so adjusted that 85 at each downward movement of the casing carrying the alternating wheel the pawl will cause the said wheel to make one-eighth of a revolution, presenting a blank and an aperture alternately to the lower end of the stem K', the blank being presented in the path of the said piston on an exhaust stroke when valve K is opened about one-half throw of eccentric. 90

From the construction hereinbefore de- 95 scribed, and illustrated in the drawings, it will be noted that the tension of the spring Q is greatest after the valve is seated, by reason of the abutment-nut O still continuing its downward stroke. As a blank in the alter- 100 nating wheel is presented an exhaust occurs. Both abutting ends of the spring move with the valve, so tension of the spring is not increased as the exhaust-valve is raised from its seat, which is considered a great desider- 105 atum in our invention.

We are aware that it is common in explosive gas-engines to provide a governing mechanism which automatically regulates the supply of gas to a cylinder and also a means for 110 controlling the exhaust products of the explosive gases, and hence we do not claim, broadly, any such mechanism.

Having thus described our invention, what we claim to be new, and desire to secure by 115 Letters Patent, is—

1. A device for controlling the feed of gas to the cylinder of an explosive-engine, consisting of a vertically-movable valve-stem having an elongated slot, a hardened-steel block having a beveled surface, seated in said slot, combined with the horizontally-movable shaft passing through said slot, the underside of the said shaft having a beveled surface a 120

portion of its length which is adapted to be held in a plane parallel to the beveled surface of the said steel block, the outer end of the shaft being screw-threaded and carrying adjusting-nuts, and an operating-lever held between said nuts and means for operating the said lever, substantially as shown and described.

2. A device for regulating the supply of gas to a cylinder of an explosive gas-engine, consisting of the valve-stem E' slotted longitudinally, the steel beveled block held therein, combined with the shaft G having the under side of its head beveled and an integral step g thereon, the outer end of the said shaft being screw-threaded, the adjusting-nuts H having hubs mounted on the screw-threaded portion of the shaft, and the pivoted lever I having a slot near its upper end through which the said shaft passes, and the spring interposed between the upper end of the said lever, and the casing carrying the valve-rod, the lower end of the lever I being connected with a collar which is moved backward and forward by a governor, substantially as shown and described.

3. In combination with the feed-valve stem as described carrying the reversible beveled steel block in a slot therein, the reversible shaft G, having a series of steps on its upper side, and a beveled surface with an integral lug or step on its lower face, and means for reciprocating the said shaft, substantially as shown and described.

35 4. A regulating device for an exhaust-valve in an explosive-engine, consisting of the exhaust-valve stem K' the reciprocating casing

carrying the same, and spring interposed between the upper end of the casing and a jam-nut on the piston-rod, an alternating wheel 40 mounted at the lower end of the said casing, and means for reciprocating the latter, and for revolving the alternating wheel.

5. A regulating device for the exhaust-valve of a gas-engine, consisting of the reciprocating casing M, nut O, the crank and pitman for operating the same, combined with the stem K' mounted in said casing, a portion of the length of the said stem being screw-threaded, jam-nuts working on said threads, 50 the spring interposed between the jam-nuts and the nut O, and the alternating wheel journaled at the lower end of the casing, and a ratchet-wheel and a swinging pawl designed to rotate the ratchet-wheel which causes the 55 alternating wheel to make partial revolutions, substantially as shown and described.

6. In combination the casing, the stem carried thereby, the shaft journaled in the said casing, the alternating wheel mounted on said shaft, the friction-spring n, the ratchet-wheel N² and the swinging pawl mounted as described and designed to engage with the teeth of the ratchet-wheel as the casing carrying the ratchet-wheel is lowered, but to swing laterally as the ratchet-wheel rises, substantially as described.

In testimony whereof we affix our signatures in presence of two witnesses.
